UNITED STATES PATENT OFFICE.

WILLIAM ATKINS, OF AUBURN, NEW YORK, ASSIGNOR, BY DIRECT AND MESNE ASSIGNMENTS, OF THREE-FOURTHS TO ELMORE N. ROSS AND WILLIAM A. TICE, BOTH OF AUBURN, NEW YORK.

WAGON-TRAIN.

14,639.

Specification of Reissued Letters Patent. Reissued Apr. 29, 1919.

Original No. 1,122,241, dated December 29, 1914, Serial No. 582,678, filed September 19, 1910. Application for reissue filed May 22, 1916. Serial No. 99,949.

To all whom it may concern:

Be it known that I, WILLIAM ATKINS, a citizen of the United States of America, and resident of Auburn, in the county of Cayuga, in the State of New York, have invented new and useful Improvements in Wagon-Trains, of which the following, taken in connection with the accompanying drawings, is a full, clear, and exact description.

This invention relates to certain improvements in wagon trains, and refers more particularly to two-wheel trucks or carts of the centrally-balanced-body type to be used in train in the construction of highways, road beds and for other purposes.

In the construction of highways, road beds, canals and other similar projects in which extensive excavations and fills are required, the conveniences for loading and hauling materials vary considerably along the line or at different localities so that in some places, it will be possible to operate a train of two-wheeled trucks or carts by means of a traction engine or other mechanical or animal power, while in other places it would be impracticable to operate more than a single two-wheeled cart by the same or different power.

Furthermore, in this class of work where four-wheeled dump wagons are now most commonly employed, the running gear as well as the box or body are frequently subjected to excessive strains, due to the irregularity of the surface over which they travel, thereby causing unavoidable breakage and incurring a large expense for repairs and replacement of the wagon.

The main object of my invention is to obviate, so far as practicable, the difficulties attending the use of the ordinary dump wagon by using two-wheeled sections or carts connected together in such manner as to permit a wide range of flexibility or independent lateral movement of either unit relatively to the other.

Another object is to provide means whereby the units may be coupled together in

definitely for use as a train drawn by a single motive power, as for example a traction engine, or uncoupled and used independently in connection with the same or a different motive power.

A further object is to provide means whereby two units may be coupled together end to end in such manner that the coupling may serve to carry the adjacent ends of both units and hold them against relative tilting movement about the axes of their respective supporting wheels, and at the same time to allow either unit to turn laterally relatively to the other about a comparatively short radius in turning corners.

A still further object is to couple the several units together in pairs in such manner that each pair may rock vertically and transversely relatively to the next adjacent pair and thereby automatically adjust themselves to irregular road surfaces without overstraining any of the connecting or connected parts.

Other objects and uses relating to the couplings and also to the mechanism for controlling the operation of the bottom doors will be brought out in the following description.

In the drawings—

Figures 1 and 2 are, respectively, a top plan and a side elevation of a wagon train comprising, in this instance, two wagons or four cart sections embodying the various features of my invention.

Figs. 3 and 4 are transverse sectional views taken, respectively, on lines 3—3 and 4—4, Fig. 1, showing opposite ends of the same wagon section and the proper forms of couplings connected thereto.

Fig. 5 is a side elevation, partly in section, of one of the wagon boxes showing the couplings and door-operating mechanism.

Figs. 6 and 7 are, respectively, an inverted plan and an opposite side elevation of the same box.

Fig. 8 is an enlarged longitudinal vertical sectional view, partly in elevation, of

the couplings between two carts forming a wagon.

Fig. 9 is a top plan, partly in section, of the couplings shown in Fig. 8.

Fig. 10 is an enlarged longitudinal sectional view, partly in elevation, of the couplings between two carts.

Fig. 11 is a top plan, partly in section, of the same coupling shown in Fig. 10.

In order that my invention may be clearly understood, I have shown in Figs. 1 and 2 a train of, in this instance, four two-wheeled carts or units —1—, each comprising a dump box or body —2— centrally mounted upon an axle —4— having wheels, as —3—, which are shown by dotted lines, so that each body is approximately balanced at the axis of its wheels, said box having downwardly and inwardly inclined ends —5—, the lower edges of which are disposed in substantially the same plane as, and the same distance from, the axle —4— forming intervening openings —6— which extend from side to side of the box.

These openings are adapted to be closed by separately movable doors —7— corresponding in area to that of their respective openings, each door being hingedly supported substantially midway between its front and rear edges upon one or more forwardly and rearwardly extending hinge bars —8— which are pivoted at their outer ends to fixed hinge sections —9— on the inclined ends of the box so that the axes of the doors and their movable supporting bars —8— are substantially parallel and extend transversely of the box in such manner as to effectively close the opening and permit independent swinging motion of the doors upon the supporting bars —8— when said doors are opened.

The object of this independent movement of the doors is to permit them to more readily clear themselves from the discharged load or other obstacles as the wagon or train is moving. The doors —7— are of sufficient length from front to rear to extend along the lower edges of the inclined ends —5— and axle —4— when in their closed position and under such conditions are tightly drawn against said lower edges or faces by their operating mechanisms, presently described, thereby reducing the liability of accumulations of dirt or other foreign matter at the joints which might interfere with the positive closing of the doors.

Each unit —2— is equipped with a separate door-controlling mechanism consisting, in this instance, of a single chain or cable —10— having its ends extended transversely under the inner edges of the doors through suitable guides —11— and secured by hooks or similar fastening means —12— to the outer face of one side of the box, as best seen in Fig. 7, the intermediate portions of said

chain being passed around idlers —13— on the opposite side of the box and around a suitable sheave —14— at the same side.

This sheave —14— is mounted in a yoke —15— which is connected by a separate cable —16— to a rotary drum —17—. The drum —17— is secured to the outer end of a rotary tubular shaft —18— which extends transversely of and is journaled in suitable bearings in the sides of the box just outside of one of the ends.

The draw-heads —36— and their connecting rod —35— constitute a specific form of coupling device for connecting the adjacent ends of the carts of each pair, the draw-heads —36— being hingedly connected by pivotal bolts —39— to and between separate pairs of cross-bars or guide plates —40— which are rigidly secured to the adjacent ends of said carts in parallel spaced relation so as to bear against the lower and upper faces of the draw-head —36— some distance from the bolts —39— to carry the adjacent ends of both carts and hold them against tilting movement about the axes of their respective supporting wheels.

The space between the bars or plates —40— preferably extends from side to side of the carts or trucks to allow either truck to turn laterally about a comparatively short radius as in turning corners.

The draw-head —36— on the forward end of the succeeding cart may be locked against lateral swinging movement in one direction or in opposite directions relatively to its guide plates —40— by means of one or more, in this instance two, stop pins —41— which are passed vertically through registering apertures in the plates —40— and in close proximity to opposite sides of the outer end of the draw-head when the draw-head is centrally positioned or parallel with the lengthwise center of the box, as best seen at the right of Fig. 11, so that by removing one bolt the remaining bolt will prevent the swinging of one of the pivotally connected units in one direction and permit its swinging movement in an opposite direction.

Each end of the draw-rod —35— is yieldingly connected for relative lengthwise movement to one of the draw-heads —36— by means of a coiled spring —42— which, in this instance, is arranged in a central opening —43— in the draw-head and is interposed between suitable shoulders or washers —44— and —45— surrounding the adjacent portion of the draw-rod. The washer —45— abuts against one end of the opening —43—, while the washer —44— is spring-pressed by the spring —42— against a limiting stop —46— on the draw-rod.

This draw-rod is slidable endwise in a corresponding opening —47— extending inwardly from the outer end thereof to a point in proximity to the pivotal bolt —39—

where it terminates against an abutment 48— normally engaged by the corresponding end of the draw-rod 35— to limit the endwise movement of said draw-rod in that direction. The opening 47— is of substantially the same cross sectional form and size as the draw-rod 35—, leaving just sufficient clearance to permit the latter to slide freely therein.

10 It, therefore, follows that when the wagon sections are connected in train, the ends of the sections of each wagon are prevented from relative vertical movement, but at the same time the leading wagon section is 15 allowed to rock laterally upon the pivotal bolt 39— while the section immediately following is held against such lateral swinging movement by the pins 41—, thus permitting the leading cart of each wagon to 20 serve as a steering section for the succeeding section.

In some instances, it is impracticable or 25 undesirable to turn the entire train around end for end, under which conditions the motive power, such as a traction engine, may be 30 detached from the previously fastened end and connected to the opposite end of the train, whereupon it is simply necessary to remove the pins 41— from the plates 40— 35 in which they were previously placed and to replace them in the corresponding apertures of the plates 40— of the adjacent cart which then becomes the follower.

It may be desired to remove the draw- 40 heads to permit them to be used in connection with other wagon sections, and for this purpose, the pivotal bolts 39— are removable, being held in place by cotter keys or equivalent detachable fastening means.

45 When the draw-heads are removed from between the plates 40— they may be readily detached from the draw-rods 35— by simply removing the stop pins 46— through the opening 43—, thus permitting the rod 35— to be withdrawn from the draw-heads 36— and washers 44— and 50 45— and spring 42— and allowing the corresponding end of the draw-rod to be attached to a traction engine or other motive power.

In the construction or surfacing of highways, it may be desirable to utilize the wheels for rolling as large surface area as possible by shifting one or more of the 55 carts out of alignment with the others, and for this purpose, the platforms or plates 40— are provided with a transverse row of two or more, in this instance three, bolt openings 50— for the reception of the 60 pivotal bolt 30—, said platform being also provided with a plurality of sets of apertures 51— for the reception of the stop pins 41—, thus permitting either draw-head 36— to be shifted laterally to different 65 positions from the longitudinal center

of the box and thereby causing the wheels of adjacent wagon sections to travel side by side in different paths for the purpose of rolling a greater surface area as the wagon or train is drawn in one direction or the other.

Each of the draw-heads 38— is adapted to swing or rock laterally between horizontal guide plates 52— in a manner similar to the draw-heads 36—, and for this purpose, the inner end is hingedly connected to the plates 52— by a pivotal bolt 53— which is passed through a set of registering bolt openings therein and is held in place by a cotter key 54— so that the pivotal bolt may be removed to permit the removal of the draw-head when desired or necessary.

These plates 52— are secured to the end of the wagon box or section 2— opposite that to which the plates 40— are secured, 85 but are spaced apart vertically a greater distance than the plates 40— to permit vertical rocking movement of the corresponding end of the draw-rod 37— therein, as will be hereinafter described, the outer 90 end of each draw-head being fitted with an easy sliding fit between the plates 52— to prevent relative vertical movement of said plates and draw-head.

These draw-heads 38— are provided 95 with central lengthwise openings 55— of greater vertical height at the inner ends than the diameter of the draw-bar to thereby allow the corresponding wagon sections to tilt endwise vertically relatively to each other, the transverse width of the openings being just sufficient to permit the free vertical rocking movement of the heads and rods relatively to each other and preventing relative lateral movement of the same parts. 100

When the wagons are connected together in train, the draw-bars 37— extend centrally through the openings 55— to points in proximity to the pivotal bolts 53— and play between the lower and upper sides of 110 the inner ends of the draw-heads, which sides are spaced apart vertically for this purpose.

This draw-bar is preferably round in cross section and is journaled in a suitable rock shaft or cross head 56— having opposite laterally projecting trunnions or journals 57— which are journaled in bearings 58— in the adjacent ends of the sides of the draw-heads and are held in place by 120 removable pins 59—, the latter being passed through registering apertures in opposite sides of the bearing 58— to prevent withdrawal of the rock shaft from the draw-head through the open side of the 125 bearing, and at the same time permitting the same rock shaft to be removed when necessary by simply removing the pins 59—.

These rock shafts 56— are, therefore, journaled in the adjacent open ends of the 130

draw-heads —38— to permit relative endwise tilting of the draw-heads and carriages upon which they are mounted, under which conditions the inner ends of the draw-rods 5 play vertically in the openings —55—.

The draw-heads —38— and their connecting rod or bolt —37— also constitute a coupling device for connecting the ends of the several pairs of carts, but differ from the 10 couplings which connect the carts of each pair in that the hinged joint formed by the trunnions —57— and draw-heads —38— permit them to flex vertically to prevent overstraining of the connections as the train 15 passes over uneven road surfaces.

It is also apparent that by journaling the draw-rod —37— in the rock shafts or cross heads —56—, the carriages upon which said draw-heads are mounted may also rock or 20 tilt transversely relatively to each other, the same being also true of the carriages which are connected by the draw-rod —35— and draw-heads —36—.

The draw-bar —37— and its corresponding draw-heads —38— are yieldingly connected for relative endwise movement by coiled springs —60— which encircle the opposite ends of the draw-rod between limiting stops —61— and —62— consisting, in 30 this instance, of washers which are loosely mounted upon the draw-rod.

The washer —61— is held against the inner face of the rock shaft or cross head —56— by the adjacent end of the spring 35 —60—, while the washer —62— is held against a stop pin —63— by the adjacent end of the same spring which, therefore, tends to force the draw-rod endwise inwardly, but such movement is limited by a 40 stop shoulder consisting of a washer —64— which normally engages the outer end face of the rock shaft or cross head —56— and is held in position by a stop pin —65—, as best seen in Figs. 8 and 9.

45 It is now clear from the foregoing description that the draw-rod and rock shafts are free to turn and to move endwise relatively to each other with or against the action of the springs —60—, which latter serve as 50 shock absorbers or buffers to prevent sudden jerks or excessive strains upon the connections between the wagons or wagon sections when starting or in transit from one place to another, the same also being true 55 of the springs —42— between the draw-rod —35— and their corresponding draw-heads —36—.

In order that the wagons or wagon sections which are coupled together by the 60 draw-rod —37— and draw-heads —38— may be shifted laterally relatively to each other to cause their wheels to travel out of alignment for the purpose of rolling a greater area of road surface, the plates —52— 65 are provided with a transverse series of, in

this instance three, apertures —66— for the reception of the pivotal bolt —53—, said plates being also provided with a plurality of sets of apertures —67— for the reception of locking pins —68— by which the corresponding draw-head may be locked against a lateral swinging movement upon the corresponding pivotal bolt —53—, as best seen at the right of Figs. 8 and 9.

These pins —68— serve the same purpose 75 in connection with the draw-heads —38— as the pins —41— for the draw-heads —36—, and when the carriages are connected in train the locking pins are only inserted in the front end of each succeeding carriage, 80 leaving the rear end of the preceding carriage and its draw-head free to rock relatively to each other, whereby each preceding carriage serves to steer or guide the next succeeding carriage.

Like the draw-heads —36—, the draw-heads —38— may be readily removed from between the plates —52— by simply removing the pivotal bolt —53—, while the draw-bars —37— may be also readily removed 90 from the draw-heads by simply removing the pins —59—, thus permitting quick removal of the springs —60— and washers —61— and —62— by withdrawing the pin —63—.

In this manner, either of the carriages may be detached from the corresponding end of the draw-bar, which end is equipped with means, as an aperture —70—, for receiving a suitable bolt or pin by which it may be 100 readily attached to a traction engine or other motive power.

What I claim is:—

1. A wagon train composed of two-wheel cars, each car having its opposite ends provided with separate pairs of opposed plates, hollow draw-heads pivoted to and between their respective pairs of plates, draw-bars extending into their respective draw-heads, and a rocking member journaled on one of the draw-bars and pivotally connected to the corresponding draw-head.

2. A wagon train having the opposite ends of each of its units provided with separate pairs of fixed plates spaced apart vertically, hollow draw-heads pivoted at one end to and between their respective pairs of plates, draw-bars extending into their respective draw-heads, and a rocking member journaled on one of the draw-bars and pivoted 110 to the corresponding draw-head to swing in a plane at right angles to that of said draw-head.

3. A wagon train having each of its units provided with an axle and a dump box centrally mounted upon the axle, separate draw-heads pivoted to opposite ends of the box, and separate draw-bars connected to their respective draw-heads for relative rotary movement, one of said draw-bars being 125 130

pivoted to its draw-head for independent rocking movement.

4. A wagon train having each of its units provided with an axle and a dump box centrally mounted upon the axle, separate draw-heads pivoted to opposite ends of the box, separate draw-bars connected to their respective draw-heads for relative rotary movement, one of said draw-bars being pivoted to its draw-head for independent rocking movement, and means for holding the other draw-bar against rocking movement relatively to its draw-head.

5. A wheel-carriage having its opposite ends provided with laterally swinging draw-heads, separate draw-bars rotatable in said draw-heads, means for holding one of the draw-heads and its corresponding draw-bar against relative vertical movement, and a rocking connection between the other draw-head and its corresponding draw-bar.

6. A wheel-carriage having its opposite ends provided with laterally swinging draw-heads and separate draw-bars slidably end-wise in the draw-heads, each draw-head and its draw-bar being rotatable one upon the other, a rocking support journaled on one of the draw-heads and provided with an opening in which the adjacent draw-bar is slidably, yielding connections between said draw-bar and support, separate yielding connections between the other draw-head and its corresponding draw-bar, said yielding connections acting in the direction of length of said draw-bars.

7. A wagon train having each of its units provided with an axle and a bottom-dump box centrally secured thereto, a draw-head

pivoted at one end to one end of the dump box, a cross head journaled on the opposite end of the draw-head and provided with an opening therethrough, a draw-bar extending through said opening and yielding connections between the draw-bar and cross-head.

8. The combination of a plurality of two-wheeled trucks in tandem, each truck having a body substantially balanced at the axis of the wheels, a coupling connecting adjacent ends of two of the bodies and including separate vertical pivots about which either body may swing laterally, and means on one of the bodies coöperating with the coupling for locking said body and coupling against relative lateral movement, said coupling having a portion thereof pivoted to swing vertically.

9. The combination of adjacent units of a wagon train, and a coupling connecting said units, said coupling having two pairs of hinge-joints, the axes of the joints of each pair being disposed at substantially right angles to the axes of the joints of the other pair to permit either of said units to swing about either or all of said axes, and means for preventing the swinging movement of one of said units in one direction and permitting its swinging movement in an opposite direction about one of said axes independent of the swinging movement of both units in reverse directions about the remaining axes.

In witness whereof, I have hereunto set my hand this 12th day of April, 1916.

WILLIAM ATKINS.
